UNITED STATES PATENT OFFICE.

LOUIS BERG, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM FUEL-FEED DEVICE.

1,277,684.

Specification of Letters Patent. Patented Sept. 3, 1918.

Application filed September 10, 1917. Serial No. 190,678.

To all whom it may concern:

Be it known that I, LOUIS BERG, a citizen of the United States, residing at Chicago, in the county of Cook and State of Illinois, have invented new and useful Improvements in Vacuum Fuel-Feed Devices, of which the following is a specification, reference being had to the accompanying drawings, forming a part thereof.

10 The purpose of this invention is to provide an improved construction in a vacuum fuel feeding device for controlling the alternation of domination of the suction and atmospheric pressure in the vacuum chamber.

15 It consists in the elements and features of construction shown and described, as indicated in the claims.

In the drawings:

Figure 1 is a side elevation of a vacuum fuel feed device embodying this invention, having the wall of the vacuum chamber broken away to disclose the interior structure.

Fig. 2 is a vertical section axial with respect to the atmosphere valve stem and buoys.

Fig. 3 is a view similar to Fig. 2, showing the operating parts in a different position.

In the drawings 1 represents the main low level supply tank for the liquid fuel. 2 is the vacuum chamber of the feed device located at a higher level. 3 is a conduit for conducting the liquid fuel from the tank, 1, to the vacuum chamber, 2. 4 is a reservoir or receptacle into which the liquid fuel is delivered by gravity from the vacuum chamber for supplying the carbureter in the usual manner by gravity flow from said reservoir, 4. In the form shown in Fig. 1 there is provided a rigidly supported vertical guide, 6, whose support is obtained by means of two posts, 7, 7, upstanding from the bottom plate, 8, of the vacuum chamber, and connected at their upper ends by a cross-bar, 9, from which said vertical guide depends rigidly. On this guide there are mounted two buoys, 10 and 11, the lower buoy, 10, being quite small relatively to the upper buoy, 11, and said lower buoy having rigidly connected to it at its lower side the valve, 12, for controlling the atmosphere inlet port which is obtained through a nipple, 14, screwed through the said bottom plate, 8, and connected below said bottom plate with a pipe, 15, which extends along the under side of the bottom plate, and thence up at the side of the vacuum chamber in the annular space, 5, between the same and the outer wall, 16, of the reservoir, 4. On the rigid vertical guide, 6, there are fulcrumed two bell-crank levers, having outwardly-extending arms, 20, which engage with up-standing eyes, 22^a, formed on a bar, 22, which is secured upon the top of the lower buoy, whereby the bell-crank levers are operatively engaged with said buoy. The upstanding arms, 21, of the bell-crank levers, are spaced away from the central guide stem by a distance sufficient to admit between them when the outwardly-extending arms are at the lowest position, a hub-like projection, 24, which extends down from the lower side of the upper buoy, 11, and when entered between said up-standing arms of the bell-crank levers, locks them at the low position of their outwardly-extending arms, and thereby locks the lower buoy at the corresponding low position which is the closed or seated position of the valve, 12, cutting off the atmospheric pressure. When the upper buoy is lifted, withdrawing its hub, 24, from between the upstanding arms of the bell-crank levers, the lower buoy is unfrocked and is left free to rise, which will happen instantly when the float has been lifted far enough to withdraw the lower shoulder of said hub, 24, past the upper point of the upstanding arms, 21, of the bell-crank levers. The vacuum chamber is provided with a suction or exhaust connection shown at 26, and the liquid content is transferred from said chamber, when the atmospheric pressure is admitted, through a short discharge duct, 27, past the check valve, 28, in the familiar manner. It is to be understood that the reservoir, 4, within the annular space at the upper part thereof around the vacuum chamber, is at all times open to atmospheric pressure through a tube, 25, which may conveniently be inserted through the plate, 29, which forms the top of the vacuum chamber through which the liquid fuel exhaust connections are made.

The operation of the device may be understood from the foregoing description, but may be furthermore particularly explained. The vacuum chamber, 2, being empty and connected through the suction tube, 26, with the engine manifold or other

105
110

source of suction, the vacuum being produced in said vacuum chamber causes the liquid to rise from the low-level main supply tank 1, and be discharged into said 5 vacuum chamber through the pipe, 3. It will be observed that initially, that is, when the vacuum chamber is empty, the lower buoy, 10, will be at its lowest position, holding the valve, 12, seated, and the atmospheric 10 pressure excluded, and that the upper buoy will also be at the lower position with its hub, 24, engaged between the upstanding arms 21, of the bell crank levers, 20, 21, locking the lower buoy down and the valve 15 closed. As the liquid rises in the vacuum chamber, it first tends to uplift the lower buoy, but that buoy being locked at its lower position, remains at that position holding the atmosphere valve closed, while the buoy 20 becomes submerged in the liquid. The liquid continuing to rise, eventually reaches and partly submerges and eventually uplifts the upper buoy, withdrawing its hub, 24, from between the upstanding arms of the bell- 25 crank levers, and releasing them so that the lower buoy can rise, which it will do upon the instant that the lower shoulder of said hub passes the upper ends of the bell-crank lever, thus causing the atmosphere valve to 30 remain completely closed until it is instantly and fully opened. The atmosphere inlet being quite large relatively to the suction port, which is continuously open, atmospheric pressure will dominate over the suction al- 35 most instantly upon the opening of the atmosphere inlet valve as described; and thereupon the liquid contents of the vacuum chamber will escape therefrom by gravity past the valve, 28. As the liquid level is 40 lowered in the vacuum chamber, the upper buoy ceasing to be upheld by the liquid, would tend to fall, but cannot do so so long as the lower buoy remains upheld, holding the bell-crank levers with their upstanding 45 arms engaged under the lower shoulder of the hub, 24. No change in the valve situation occurs, therefore, until the liquid level has fallen so low as to permit the lower buoy to drop a sufficient distance to withdraw the 50 upstanding lever arms from under said shoulder, whereupon instantly the upper buoy falls, thrusting its hub between the upstanding arms of the levers, and by virtue of the slight taper which that hub has as 55 shown, spreads the upstanding lever arms, and thereby causes the outwardly-extending arms of the levers to force the lower buoy down, somewhat hastening its descent, and causing the closing of the atmosphere inlet 60 valve to be substantially instantaneous, and to occur when the liquid level in the vacuum chamber has fallen to a predetermined level which is a level at which the lower buoy is partly submerged.

65 It will be observed that the structure de-

scribed, involving the two buoys, and the locking devices coöperating between them, produces delayed action of the atmosphere valve both in opening and closing, until that action can be performed abruptly, thus performing the function of the familiar snap action, requiring more or less complicated mechanism for its performance. 70

I claim:—

1. In combination with a main low level 75 liquid fuel supply tank, an elevated vacuum chamber; a conduit for liquid fuel from the main supply tank to the vacuum chamber; a valve adapted to be held on its seat by suction in the vacuum chamber, and past 80 which the liquid may be discharged by gravity from said chamber, the vacuum chamber having a suction or exhaust connection and an atmosphere inlet port; a valve controlling the atmosphere inlet port; an upper buoy and a lower buoy in the vacuum chamber; means by which one of said buoys operates the atmosphere inlet valve, and means by which the other buoy locks the valve 85 against such operation in one direction. 90

2. In a construction such as set out in 95 claim 1 foregoing, the atmosphere valve being operated by the lower buoy, and means by which the upper buoy locks the valve closed until said upper buoy rises. 95

3. In a construction such as set out in 100 claim 1 foregoing, the valve being operated by the lower buoy, and locking devices carried by the upper buoy for locking the lower buoy down until the upper float rises. 100

4. In a construction such as set out in 105 claim 1 foregoing, the valve being operated by the lower buoy, and locking devices operatively engaged with the lower buoy for locking the upper buoy up until the lower buoy falls. 105

5. In a construction such as set out in 110 claim 1, foregoing, the atmosphere valve being operated by the lower buoy, and locking devices operating between the two floats 110 for locking the upper buoy up until the lower buoy falls, and the lower buoy down until the upper float rises. 110

6. In a structure such as set out in claim 115 1, foregoing, a fixed guide for the lower buoy, a bell-crank lever fulcrumed on said guide, having an outwardly-extending arm engaged with the buoy, the upper buoy being mounted and guided co-axially with the lower buoy and provided at the lower end 120 with a shoulder under which the upstanding arm of the bell crank lever is engaged by the upward movement of the lower buoy when the upper buoy is raised, whereby said upper buoy is held locked at elevated position. 125

7. In a structure such as set out in claim 1, the atmosphere inlet port being at the bottom of the vacuum chamber and a pipe leading therefrom upwardly alongside said chamber substantially to the high liquid 130

level thereof; a rigid guide for the buoys positioned overhanging said inlet port, the lower buoy having the atmosphere inlet valve rigid with it and the upper buoy being free from the valve.

8. In a structure such as set out in claim 6, foregoing, a tapered hub on the lower side of the upper buoy whose lower end constitutes the shoulder mentioned, said tapered

hub being adapted for encounter by the up-standing lever arm and by its said taper to wedge said lever arm in the direction for crowding the atmosphere valve to its seat.

In testimony whereof, I have hereunto set my hand at Chicago, Illinois, this 30th day 15 of August, 1917.

LOUIS BERG.
